UNITED STATES PATENT OFFICE.

CHARLIE L. CAIN, OF BLACKFORD, KENTUCKY, ASSIGNOR OF ONE-FOURTH TO
WILLIAM D. CROWELL, OF MARION, KENTUCKY.

CROSSTIE.

1,427,062.

Specification of Letters Patent. Patented Aug. 22, 1922.

Application filed March 7, 1922. Serial No. 541,705.

To all whom it may concern:

Be it known that I, CHARLIE L. CAIN, a citizen of the United States, residing at Blackford, in the county of Webster and State of Kentucky, have invented new and useful Improvements in Cross Ties, of which the following is a specification.

This invention comprehends the provision of a metallic railroad tie equipped with a novel construction of means, whereby the rails of the track can be quickly and effectively clamped upon the tie, or removed therefrom as the occasion may require, the invention residing in the construction, combination, and arrangement of parts as claimed.

In the drawings forming part of this application, like numerals of reference indicate similar parts in the several views and 20 wherein:

Figure 1— is a top plan view of the tie.

Figure 2— is a longitudinal sectional view.

Figure 3— is a transverse sectional view taken on line 3—3 of Figure 1.

Figure 4— is a detail view of one of the adjustable casings.

Figure 5— is a perspective view of one of the rail clamps and its connecting bolt.

Referring to the drawings in detail, 30 indicates a metallic tie of hollow rectangular formation in cross section. The tie is open at both ends to receive the adjustable casings 11, there being one of these casings arranged in each end of the tie and mounted for sliding movement for a purpose to be presently described. The upper wall of the tie 10 is cut away immediately over each casing as at 12, the rail 13 bridging said opening as illustrated in Figure 1. The upper wall of the casing 11 is provided with two oppositely disposed key-hole slots 14 which are arranged along the longitudinal center of the casing to accommodate the headed bolts 15 cooperating with the rail clamps 16. The clamps 16 may be of any suitable wellknown construction, and are designed to embrace the base of the rail 13 to hold the rail immovably positioned upon the tie. It will be noted, that drainage space is provided between the base of the rail, and the top wall of the casing 11 to prevent the accumulation of water or the like.

55 The heads of the bolts 15 are positioned

within the key-hole slots above referred to, after which the casings 11 are singly adjusted to adjust the gage of the rails. In order to effect an adjustment of the casings 11 each is equipped with an adjusting rod 17 having a head 18 which is swiveled in the adjacent end of the casing 11, the rod 17 being threaded as at 19, the threaded portion operating through a block 20 which is secured within the tie by fastening elements 21. The outer extremity of each rod 17 is squared as at 22 to accommodate a wrench of suitable construction, so that the rods may be turned in either direction to slide the casing within the tie. The movements 70 of the casings 11 obviously adjust the gage of the rails. The construction is very simple, and the tie in its entirety can be manufactured and sold at a very nominal cost.

While it is believed that from the foregoing description, the nature and advantages of the invention will be readily apparent, I desire to have it understood that I do not limit myself to what is herein- 80 shown and described, and that such changes may be resorted to when desired as fall within the scope of what is claimed.

What I claim is:

1. In combination with a metallic tie having an opening in the upper wall thereof, of a casing insertible in each end of the tie and arranged beneath said opening, rail clamps with headed bolts, the upper wall of said casing having oppositely disposed key-hole slots for the reception of said bolts, and means for adjusting said casing longitudinally of the tie for the purpose specified.

2. The combination with a hollow metallic tie having an opening in the upper wall thereof, of a casing arranged within the tie beneath said opening, said casing having oppositely disposed key-hole slots, rail clamps with headed bolts fitted within said slots, a rod having a head swiveled in the end of said casing and projecting from the adjacent end of the tie, said rod having a threaded portion, a block arranged within the tie and having a threaded opening in which the threaded portion of the rod 105 operates, whereby said casing may be adjusted longitudinally of the tie for the purpose specified.

In testimony whereof I affix my signature.
CHARLIE L. CAIN.
